US0D1037483S

(12) **United States Design Patent** (10) **Patent No.:** **US D1,037,483 S**
(45) **Date of Patent:** **** Jul. 30, 2024**

(54) **SAMPLE COLLECTION DEVICE**

(71) Applicant: **Cue Health Inc.**, San Diego, CA (US)

(72) Inventors: **Clint Sever**, San Diego, CA (US);
Joseph D. Kowalski, San Diego, CA (US);
Michael Yep, San Diego, CA (US);
Eric E. Johnson, San Diego, CA (US)

(73) Assignee: **CUE HEALTH INC.**, San Diego, CA (US)

(**) Term: **15 Years**

(21) Appl. No.: **29/830,844**

(22) Filed: **Mar. 15, 2022**

(51) LOC (14) Cl. **24-02**

(52) U.S. Cl.

USPC **D24/224**; D24/216

CLAIM

We claim the ornamental design for a sample collection device, as shown and described.

DESCRIPTION

FIG. 1 is a top, rear, left side perspective view of a sample collection device;

FIG. 2 is a bottom, rear, right side perspective view thereof; FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

1 Claim, 5 Drawing Sheets
